ELECTRIC SIGN

Morris Bernstein and Harold C. Dubroff, Brooklyn, N. Y., assignors to Ethical Display Co., Inc., Brooklyn, N. Y., a corporation of New York

Application October 24, 1933, Serial No. 695,042

1 Claim. (Cl. 40—132)

This invention relates to electric signs and more particularly to such signs adapted to be placed against a window and to be secured to the inner surface of the frame of the same.

5 One of the objects of the invention is the provision of an electric sign of the character described and which may be illuminated by a lamp within a casing forming part of the sign.

Other objects will be appreciated from a reading of the following specification.

The invention will be fully and comprehensively understood from a consideration of the following detailed description when read in connection with the accompanying drawing which forms 15 part of the application with the understanding, however, that the improvement is capable of extended application and is not confined to the exact showing of the drawing nor to the precise construction described and, therefore, such 20 changes and modifications may be made therefrom as do not affect the spirit of the invention nor exceed the scope thereof as expressed in the appended claim.

In the drawing:

25 Fig. 1 is a front elevation of the improved sign of my invention, the view showing the sign broken away; and

Fig. 2 is an end view, partly in section, of the sign shown in Fig. 1, the sign being shown as 30 mounted on a window frame which, together with the window, is shown in vertical section.

Referring to the drawing for a more detailed description thereof, the sign comprises a casing 5 of right angular formation in cross-section so 35 as to have a vertical portion 6 and a horizontal portion 7, the bottom 8 of the horizontal portion 7 being adapted to rest on top of the lower cross member 9 of a window sash, inside and in contact with the window 10. The free end of the 40 horizontal part 7 of the casing slidably carries a light transmitting sign 12, which bears the word "Dentist".

An elongate electric lamp 15 is disposed in the 45 vertical part 6 of the casing so as to illuminate the sign, the interior of the casing being preferably white in order to reflect light from the lamp. The back upper edge of the casing is rounded, as

indicated by the numeral 16, in order to effect a uniform diffusion of light thruout the sign and to avoid the casting of any shadows.

The sign 12, which is preferably translucent, is 5 adapted to be withdrawn through one side of the casing so that any desired sign may be placed in the casing. The lamp 15 is screwed into a socket 17 which is in the form of a right angle elbow, which abuts against and is secured to the back 10 wall of the casing, a cable 18 carrying the electrically conducting wires 19 and 20 being connected to the socket and passing through the mentioned rear wall.

When the casing is shorter than the width of 15 the window it is secured to the lower transverse member 9 of the window sash by means of brackets 21 and 22. When, however, the length 20 of the sign is equal to the width of the window, it is preferably secured to the vertical side members of the window sash by means of brackets 24 and 25, which are fastened to the sides 26 and 27, 25 respectively, of the casing.

It will be appreciated from the foregoing description that an electric sign has been provided which is neat in appearance and effective especially during the evening in interiors that are 30 dark. It will also be appreciated that a window may be raised without disturbing the sign and that its formation is such that it rests on the bottom transverse member of a window sash and, 35 further, that it will fulfill the objects of the invention.

What is claimed as new and useful is:

An illuminated sign comprising a casing having a horizontal front part and a vertical rear part, the former part having an aperture at the front thereof, a sign plate to be illuminated and positioned to close said aperture, a lamp positioned in said vertical part below said sign plate, 40 said casing being so formed that said sign plate may be positioned adjacent the inner face of the lower part of a window pane and said vertical part may be disposed adjacent the inner face of the lower transverse member of the window sash.
